CONTAINER

Guy O. Conner, Wheeling, W. Va., assignor to
Wheeling Steel Corporation, Wheeling, W. Va.,
a corporation of Delaware

Original application October 16, 1934, Serial No.
748,469. Divided and this application April 3,
1935, Serial No. 14,463

10 Claims. (Cl. 221—11)

This invention relates broadly to containers and the manufacture thereof. It relates more particularly to the manufacture of drawn sheet metal containers, and especially containers of the type adapted for the storage and transportation and dispensing of fluids, such, for example, as disclosed in my copending application Serial No. 748,469, filed October 16, 1934, of which application this application is a division, and which 10 on April 12, 1938 issued as Patent No. 2,114,137. Certain of the subject matter disclosed but not claimed herein is disclosed and claimed in my copending application Serial No. 111,897, filed November 20, 1936, which is a division of this 15 application.

The invention still further relates to certain detailed features of construction of containers of the type referred to whereby distinct advantages and increased utility are obtained, and it is the 20 purpose of this divisional application to cover certain of said features. A novel spout and closure arrangement is provided, there being means for protecting the spout against damage and keeping it clean when not in use; and means are 25 also provided for assisting in handling the container with great ease and reducing to a minimum the danger that the container will slip when being handled or when its contents are being poured.

No attempt is here made to explain all of the 30 details, objects and advantages of the invention. Other details, objects and advantages will become apparent as the following description of a present preferred embodiment of the invention 35 proceeds.

In the accompanying drawings I have shown a present preferred embodiment of the invention, in which

Figure 1 is a perspective view of a container; 40 Figure 2 is a top plan view of the container with a portion cut away and with the spout cover and closure cap removed;

Figure 3 is a fragmentary bottom plan view 45 showing a portion of the bottom of the container;

Figure 4 is a central vertical cross-sectional view taken on the line IV—IV of Figure 2;

Figure 5 is a top plan view of the closure cap; 50 Figure 6 is an elevational view of the closure cap;

Figure 7 is a top plan view of the spout cover; and

Figure 8 is a central vertical cross-sectional view through the spout cover.

55 Referring now more particularly to the draw-

ings, the invention will be described as embodied in a sheet metal container of small or medium size, such, for example, as a five-gallon can. The can is clearly shown in perspective in Figure 1, and inasmuch as the body portion thereof and the method of making the body portion do not per se constitute the invention to be claimed in this application they will not here be described in detail, but reference is made to the parent application, Serial No. 748,469, for a full description of the entire container and its manufacture.

The top closure with which this application is primarily concerned is preferably of sheet metal, as is the body of the container, and both the top and bottom closures are preferably permanently connected with the body by seaming, although the top closure may be made removable as a whole if desired. The top closure is preferably drawn into generally dome shape with rounded corners as shown so as to fit and cooperate with the drawn body blank. The top closure has a pouring opening 19 surrounded by a rim 20, being let into the top below the upper surface thereof, as shown in Figures 1 and 4. 25 Within the pouring opening 19 is a sunken sealing portion 21, and extending inwardly toward the axis of the pouring opening from opposite sides thereof at or just below the level of the rim 20 is a pair of projections 22 for a purpose 30 to be presently described. A spout 23 is drawn into the top as shown in Figures 2 and 4 and forms a smooth continuation of the rim 20. Such rim has an embossed portion 24 adapted to be punctured to provide a vent to assist in 35 pouring out the contents of the container. The spout structure, although preferably forming an integral drawn part of the top closure, may be otherwise connected with such closure, as, for example, by seaming or welding.

The top surface of the container is indicated at 25 and there is provided therein a downwardly drawn depression 26 within which is crimped at 27 a trunnion member 28 having trunnions 29 formed therein. A handle 30 is pivoted to the 45 trunnions 29 as shown and is adapted to be lifted up to enable the fingers of the hand to be passed therethrough to enable the container to be carried. When in its lower or inoperative position the handle lies substantially entirely 50 within the confines of the depression 26. The axis of the trunnions 29 may be substantially along the transverse diagonal of the top so that the handle extends substantially at right angles to the diagonal through the spout, thus enabling 55

the container to be held in a natural position when pouring out its contents through the spout. A drawn connecting portion 31 connects the depression 26 with the depression in which the pouring opening and spout are situated, this preventing the accumulation of liquid in the depression 26 and consequent submerging of the handle.

The corners of the top are rounded both horizontally and vertically as shown at 32, the material being drawn therefrom to provide ornamental portions 33, which also serve to strengthen the top, the top intermediate the corners having upwardly and outwardly facing shoulders 34 adapted to insure proper positioning thereon of another similar container stacked on top of the container. As the handle 30 is let down within the confines of the top and the top of the cap for closing the pouring opening does not extend substantially above the surface 25, the container is ideally suited for stacking, as will presently be described.

The spout 23 extends outwardly over the corner of the container so as to provide for pouring out the contents of the container therethrough, as shown in Figures 2 and 4. A spout cover 35 (Figures 7 and 8) is provided for covering the spout 23 when not in use and keeping it clean. The spout cover 35 comprises a flat annular portion 36 adapted to lie on the rim 20 and a forwardly and downwardly extending curved portion 37 to cover and protect the lip of the spout. The portion 37 terminates rearwardly on each side in a shoulder 38, these shoulders assisting in positioning the spout cover in place. Connected with the under side of the portion 36 of the spout cover is a gasket 39 adapted to lie on and seal the vent 24 after such vent has been opened and the container has later been closed. When the spout cover is in place it lies with the portion 36 on top of the rim 20 and with the portion 37 covering and closing the lip of the spout, the shoulders 38 lying outside the spout and assisting in positioning and maintaining the spout cover in place, as shown in Figure 1.

There is provided a closure cap 40 (Figures 5 and 6) which comprises a flat annular flange 41 adapted to overlie the portion 36 of the spout cover, which, in turn, overlies the rim 20 of the top of the container. Projecting downwardly centrally of the closure cap is a hub portion 42 to the bottom of which is connected a gasket 43. The gasket is adapted to seat on and cooperate with the sealing portion 21 so as to close and seal the pouring opening. At the outer surface of the hub 42 is a pair of oppositely disposed circumferentially extending cam lugs 44 adapted when the closure cap is set in place with respect to the pouring opening and rotated in the clockwise direction when viewed from above to pass beneath the projections 22 to press and maintain the closure cap tightly in place to effect a tight permanent seal between the gasket 43 and the sealing portion 21. The cam lugs 44 are forwardly tapered, as shown at 45, so that as the cap is turned a wedging engagement will be effected between the projections 22 and the lugs 44, thus insuring a tight seal. The cap has an upwardly extending hub 46 shaped to receive a wrench to turn the cap.

The closure cap 40 not only effects a tight seal at the pouring opening, but also maintains tightly in place the spout cover so as to protect the spout and keep it clean. The cap also presses the portion 36 of the spout cover against the rim

20 and particularly presses the gasket 39 down over the vent 24 to seal the vent as well as the pouring opening. A pair of oppositely disposed holes 47 is provided in the flange 41 of the cap 40 and a hole 48 is provided in the spout cover and a recess 49 is provided in the side of the exterior of the spout, as shown in Figure 2. When the spout cover is in place and the closure cap is applied and turned down to seal the pouring opening one of the holes 47 in the flange 41 of the closure cap is in alignment with the hole 48 in the spout cover, which, in turn, is in alignment with the recess 49 so that a sealing wire 56 may be passed through the holes 47 and 48 and within the recess 49 to hold the cap against turning movement relative to the spout cover. As the spout cover is prevented from turning by engagement of the shoulders 38 with the exterior of the spout, this prevents removal of the cap and maintains the container sealed until the sealing wire is broken and removed. Two holes 47 are provided at diametrically opposed portions of the closure cap, one in proper relationship with each of the oppositely disposed cam lugs 44, so that one or the other of the holes 47 will be in alignment with the hole 48 in the spout cover regardless of how the cap may be applied.

The top closure is seamed to the body blank at 50. Instead of seaming the top closure to the body blank the body blank may be provided with a suitable rim, as, for example, the usual wire bead, and a gasket may be provided adapted to be interposed between the wire bead and the sealing portion of the top closure, any suitable means of well known construction being provided for detachably connecting the top closure to the body blank.

There is provided a bottom closure member 51 having a horizontally extending main portion 52 and which is seamed to the body blank at 54. The bottom closure member is provided with drawn upward depressions 55, one at each corner, as shown in Figure 2, to assist in handling the container. In any event, it is preferable to have at least one of the depressions 55 at the bottom corner of the container opposite the corner at which the spout is situated to assist in holding the container in a natural position for pouring. One hand may grip the handle 30 and the fingers of the other hand may be inserted within the depression 55 at the corner opposite the spout, this providing a very natural and easy means for handling the container and pouring out its contents. The projections 55 also very materially strengthen the bottom and add rigidity to it.

The horizontal dimensions of the body blank at the portion 17 (see Figure 1) are greater than at the portion 16. The reason for this is explained at length in the parent application, but as this feature does not per se form any part of the invention herein claimed it will not be described in detail. However, it may be pointed out that this enables stacking of the containers one upon another as the bottom seam 54 fits down over the top of a similar container and snugly embraces the rolls 34 at the top of such similar container so that the containers are positively maintained in proper stacked relationship.

The completed container may be subjected to any suitable after-operations, such as painting, after which it is ready to be shipped out for use.

While I have shown and described a present preferred embodiment of the invention, it is to be distinctly understood that the invention is not limited thereto but may be otherwise variously

embodied within the scope of the following claims.

I claim:

1. A container having a spout and a pouring opening communicating therewith, a cover for the spout and a separate closure for the pouring opening holding the spout cover in place.

5 2. A container having a spout and a pouring opening communicating therewith, a spout cover having a portion substantially coaxial with the pouring opening and a separate closure for the pouring opening cooperating with said portion of the spout cover to hold the spout cover in place.

10 3. A container having a spout and a pouring opening communicating therewith, a cover for the spout adapted to be fitted thereover to cover and protect the spout when not in use and having an annular portion generally in line with the pouring opening, and a closure for the pouring opening having a portion extending within the annular portion of the spout cover and maintaining the same in place.

15 4. A container having a pouring opening, a sunken sealing portion within said pouring opening, and a closure for said pouring opening having a flange for closing the same exteriorly and a plug portion extending within said pouring opening into cooperative relationship with said sunken sealing portion.

20 5. A container having a spout and a pouring opening communicating therewith and a vent separate from the pouring opening, a cover for the spout having a portion covering the vent, and a closure for the pouring opening adapted to maintain the spout cover in place.

25 35 6. A container having a spout and a pouring opening communicating therewith, a non-rotat-

able cover for the spout and a rotatable closure for the pouring opening adapted to maintain the spout cover in place.

7. A container having a spout and a pouring opening communicating therewith, a non-rotatable cover for the spout, a rotatable closure for the pouring opening adapted to maintain the spout cover in place, and means preventing rotation of the closure.

5 8. A container having a spout and a pouring opening communicating therewith, a non-rotatable cover for the spout, a rotatable closure for the pouring opening adapted to maintain the spout cover in place, and means passing through openings in the spout cover and closure for preventing rotation of the latter.

10 9. A container having an outlet opening and pouring means communicating with the outlet opening and comprising a spout projecting generally laterally eccentrically with respect to the outlet opening and having a lip extending peripherally throughout a distance corresponding to a fraction only of the periphery of the outlet opening, a cover having a portion conforming to said lip and means positively maintaining the cover in operative position to close the spout regardless of the position of the container.

15 10. A container having in its top a pouring opening and having in a generally horizontally disposed portion adjacent the pouring opening a vent opening, and a closure member having a portion for sealing the pouring opening and a generally horizontally extending portion adapted to overlie the vent opening.

GUY O. CONNER.
